AIR CONDITIONING SYSTEM EMPLOYING
STEAM FOR HEATING AND COOLING

Carlyle M. Ashley, South Orange, N. J., assignor,
by mesne assignments, to Carrier Engineering
Corporation, Newark, N. J., a corporation of
New York

Application August 12, 1932, Serial No. 628,558

14 Claims. (Cl. 257—9)

This invention relates generally to air conditioning systems and more particularly to improvements in methods of and apparatus for producing both refrigeration and heating effect utilized in systems for dehumidifying, humidifying, cooling, heating, as well as controlling the temperature and relative humidity, of air.

The general object of the invention is to provide an air heating and cooling system using a common source of steam either for producing cooling effect or for producing heating effect. Thus, under one set of conditions, steam will be used for producing refrigeration, whereas, under another set of conditions, steam will be used for heating purposes, the same combination of apparatus being adapted to serve both purposes.

Another object of the invention is to provide a unitary arrangement of apparatus adapted to cool and dehumidify air volumes or to heat air volumes by employing steam from a common source, common apparatus being employed both for the dehumidifying and heating purposes.

Another object of the invention is to provide a system of apparatus in combination with a source of steam supply under a unitary control, whereby the steam may be used under one set of conditions for supplying refrigeration and under another set of conditions for supplying heating effect. The control, in practice, enables the arrangement of apparatus to operate as a heating and ventilating system, when increased temperatures are desired; and may readily convert the apparatus into a system for cooling and dehumidifying air volumes, when decreased temperatures and dehumidified atmospheric conditions are required.

A further object of the invention is to provide combined refrigerating and heating apparatus which may be operated with absolute safety, in that no dangerous refrigerants are employed, which is quiet in operation, simple in structure and capable either of heating or cooling air volumes under manual or automatic control, and whose operating cost makes for efficiency with great economy.

A feature of the invention resides in the provision of a control arrangement adapted to operate, under winter conditions, with steam pressure between certain predetermined limits, and adapted to operate under summer conditions with the steam pressure between predetermined limits at higher pressure.

Another feature of the invention resides in the use of a common conditioning apparatus

adapted to harbor a cooling medium under summer conditions and a heating medium under winter conditions, whereby air circulated in contact therewith will, under one set of conditions, be heated, and under another set of conditions be cooled and dehumidified.

Another feature of the invention provides a totally enclosed water circulation system, for carrying out refrigerating and heating processes, adapted to serve the needs of a boiler and associated refrigeration and air conditioning apparatus, losses in water supply being practically negligible and resulting only from purging operations.

Another feature provides for utilizing extremely small quantities of water for condensing steam employed for producing refrigeration, the volume of water required being substantially only that quantity which the heat of condensation is capable of evaporating and which will retain a series of condenser tubes wetted and clean.

A further object provides for supplying water for condensing purposes only when a controlled supply of steam is being utilized to produce refrigerating effect, or when the pressure within a refrigeration system rises above a predetermined limit.

A further feature of the invention provides for utilizing totally enclosed water circuits in combination with an air heating and cooling system, whereby desired water levels will be maintained in a steam boiler and evaporator forming part of the system.

A further feature provides for automatically transferring liquid from a source of supply at one pressure to a receiving means at a lower pressure, without the intervention of mechanical throttling or feed control mechanism. As a result, liquid from a condenser is fed to an evaporator without the intervention of such a device as the usual expansion valve.

A further feature provides for controlling a supply of steam for producing refrigerating effect responsive to changes in pressure of said steam supply.

A further feature comprises a steam ejector in combination with a boiler, whereby steam will be supplied to said ejector for producing desired refrigerating effect only when the steam is between predetermined pressure limits.

Another feature of the invention provides for supplying steam to a steam ejector of an air conditioning apparatus and causing an air conditioning medium to be cooled responsive to changes

in heat load affecting the atmosphere of an enclosure served by the apparatus.

Another feature resides in the provision of a combined evaporator and heat exchanger there-
5 by eliminating a pump which would otherwise be employed to circulate the fluid for a flash evaporator through a heat exchanger.

Further features, covering advantages in structure, assembly and economy, as well as flexibility
10 in operation, and assuring efficient service with complete safety under all operating conditions, will be more apparent from the following description of an illustrative arrangement of apparatus and controls adapted to carry out the
15 invention, to be read in connection with the accompanying drawings, in which:

Fig. 1 is a schematic arrangement, partly in section, of an apparatus adapted to carry out the invention, generally illustrating the interrelation of parts,

Fig. 2 illustrates diagrammatically a control arrangement to be used in combination with the apparatus of Fig. 1,

Fig. 3 is an isometric fragmentary view of a heat exchange device mounted within a duct, forming part of the invention, with a portion of the header being broken away to show the interior,

Fig. 4 is an isometric view of one of the troughs employed in the device of Fig. 3,

Fig. 5 illustrates diagrammatically an evaporator header in combination with a liquid feed system for the evaporator, and a humidifying device above the evaporator,

Fig. 6 is a diagrammatic view of a condenser employed as part of the combination of Fig. 1,

Fig. 7 is a diagrammatic representation of a boiler return trap.

Considering the drawings, similar designations referring to similar parts, and first with particular reference to Fig. 1, numeral 10 illustrates a boiler having a fire box 12, burner pipes 11, and burners 13. While the boiler may be served with any desired fuel, for purposes of illustration, gas burners are illustrated, the burners 13 being provided with controlled amounts of fuel under the regulation of valve 14. A flue 15 carried off the gases of combustion.

From the top of the boiler, pipes 16 and 17 lead to pressure reducing nozzle 18 suitably positioned in a head casing 20 and adapted to direct fluid therefrom toward an entrance diffuser 21. A valve 19 is provided in pipe 17 for controlling the admission of steam to nozzle 18, as will be hereinafter described. Conduit 22 connects head casing 20 with a header 23 of a heat exchange device, designated generally by the numeral 42, and shown in greater detail in Figs. 3 and 5. Entrance diffuser 21 leads into discharge diffuser 24 which, in turn, connects through conduit 25 with an inlet header 26 (Fig. 6) of condenser 27. The condenser 27, as shown in Fig. 6, preferably comprises an inlet header 26 and a discharge header 28 connected by a plurality of tubes 53. The tubes preferably are provided with extended surface to promote increased heat transfer. From the discharge header 28, a pipe 30 leads back to the boiler. A boiler return trap 31, whose operation will be hereinafter described, is located below the bottom of condenser 27, but above the top of boiler 10, and is connected to the pipe 30 by pipe 32. Located in pipe 30 are check valves 33 and 34 between which pipe 32 joins pipe 30.

The trap 31, shown diagrammatically in Fig. 7, 75 is of a gravity feed type containing a float 62

pivoted at 63, adapted to actuate two valves 67 and 68 in response to the movement of the float. The valves are arranged to be either fully open or fully closed and when one is open the other will be closed. A weight 64 pivoted at 65 and attached to the arm of float 62 at point 66, by an appropriate linkage, is suitably arranged to operate valves 67 and 68. When there is no liquid in the casing of trap 31 and float 62 is at its lowest position, valve 67 is open and valve 68 closed. As liquid fills the trap, the float rises, thereby moving weight 64 towards its dead center. When the level reaches a predetermined point, the weight passes its dead center and by gravity drops over, thereupon causing valve 67 to close and valve 68 to open. The movement of the weight after it passes dead center is precipitate so that the opening and closing of valves 67 and 68 will be immediate and akin to snap action. No limitation is made to the particular form of trap and any analogous means may be utilized for similar purposes, the particular means described being deemed illustrative.

Pipe 35 leads from pipe 16 to valve 68 of the return trap 31. Pipe 36 leads from valve 67 of the trap to header 26 of condenser 27 (Fig. 6) and provides an equalizing passage therebetween, whose purpose will be hereinafter described.

Heat exchanger 42 combines a plurality of functions in one apparatus and additionally provides a simple and compact apparatus readily adaptable for use under summer and winter conditions, even though operations under these varying conditions will be differently carried on. Thus, under summer conditions, it operates to cool and dehumidify air, whereas, in winter, it serves to heat the air. Furthermore, under summer conditions, it not only provides a cooling means directly for conditioning air passing in contact with component parts thereof, but also serves as an evaporator for supplying a cooling medium to said means. From a practical standpoint, it may be characterized as a condenser for heating air under winter operating conditions and as an evaporator for cooling air under summer operating conditions. Its function to avoid duplication of apparatus will be apparent.

Referring more particularly to Figs. 3, 4 and 5, 40 42 refers to a preferred form of heat exchanger having a single header 23. Tubes 29, preferably provided with extended surface, are bent in a U shape and have their ends terminating in tube sheet 59 of the header 23. As shown in Fig. 3, the ends of all U tubes in each row lie in the same horizontal plane. Attached to the ends of the tubes of each row, is a trough 60. The trough runs crosswise and below the ends of the tubes of each row, one trough being provided for each row. The tubes have open ends, so that, in effect, the tubes of each row open into the trough. The front wall of each trough 60 (Fig. 4) has a cut-out portion 61. The liquid feed pipe 72 is positioned in the top of header 23 directly above the uppermost trough 60. Hence, as under summer operating conditions, a liquid fed from pipe 72 will fall into the upper trough and enter U tubes 29 associated therewith. The depth of cut-out portion 61 of the trough is determined by the height of liquid which it is desired to maintain in the tubes associated with the trough. Therefore, when the uppermost trough and its associated tubes are filled to a desired depth, additional liquid will spill over through cut-out portion 61 and flow into the trough below. Similarly, all the lower rows of tubes and their respective troughs will be 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

filled to the desired level. Excess liquid will spill through the cut-out portion of the lowest trough and collect in the bottom of header 23, and then drain or serve a function hereinafter described. 5 The fluid evaporated in the tubes and trough finds a passageway through conduit 22 connecting the evaporator and diffuse 21.

While the single header and U tube construction of the heat exchanger is illustrated herein, 10 the invention is not limited thereto and, if desired, exchangers having oppositely disposed headers may be used to carry out similar functions.

Contiguous and on the same level with each 15 row of tubes 29 in the heat exchanger, and parallel to each of troughs 60 is a pipe 37 (Fig. 5) extending the length of header 23. The ends of pipes 37 are mounted in a header 69 (Fig. 5) which may be connected to steam supply pipe 35 (Fig. 1) by pipe 38, under control of valve 39. 20 Each of pipes 37 has a series of holes therein, a hole being provided opposite one end of each U tube 29. Steam issuing from each hole, as under winter operating conditions, is arranged 25 to enter the oppositely disposed open end of the tube. Condensate will drain out of the other end of the tube into associated trough 60. Pipe 40, containing check valve 41, joins the bottom of header 23 to pipe 32. Under winter operating 30 conditions the condensate entering troughs 60 will drain through pipe 40 back into the boiler.

Without reference to automatic features of control, which will be hereinafter described, and assuming that steam is available from boiler 10 35 at a desired pressure, that evaporator tubes 29 of heat exchanger 42 are suitably filled to the desired level, that valve 39 (used under winter conditions) is closed, and that valve 19 (used under summer conditions) is open, refrigeration operation, as desired under summer conditions, will be effected as follows. Steam from boiler 10 will proceed to nozzle 18 through pipe 16, 17 and valve 19. The steam is expanded in nozzle 18 to a predetermined pressure, for example, that at which water will boil at 45° F. Reducing the pressure at the discharge end of the nozzle causes a corresponding reduction in pressure within evaporator 42, which is in communication with the outlet of the nozzle through conduit 22 and casing 20. Consequently, heat from the air to be cooled, whose temperature is greater than 45° F., will be transmitted through the tubes 29 and cause the water therein to boil. Thus, by extracting the heat 55 from the air to supply the latent heat of evaporation to the boiling water, the air will be lowered in temperature. It is self-evident that such evaporation will produce large volumes of vapor. To prevent building up a pressure in the tubes which would impede or stop evaporation, the vapor must be removed as fast as it is produced. Its removal from tubes 29 and header 23 and through conduit 22 is accomplished by the action of the jet of high velocity steam issuing from nozzle 18. The vapor is entrained by the steam and compressed within diffusers 21 and 24 with a consequent rise in saturation temperature and pressure. The compressed mixture is then discharged through pipe 25 into inlet header 26 and tubes 53 of condenser 27. For the purpose of removing the heat of condensation, the condenser 27 is mounted within a tank 47. Water from a suitable source is fed to a spray header 48 through a pipe 49 and an aspirator 50 under the control of valve 51, and is dis-

charged on the outside of tubes 53. A fan 52 is adapted to draw air from an outside source through an opening 54 in the tank 47, through the water sprays, over the tubes 53 and to discharge the air to the atmosphere through the opening 55. The hot mixture of steam and vapor, at 100° F., for example, within tubes 53 will be condensed by giving up its latent heat to the cooler air blowing over the outside of the tubes. The tubes are kept wet by the sprays primarily to increase the transfer of heat from hot vapors to the air. By this preferred method, only sufficient water need be supplied by header 48 to keep the tubes 53 clean and wet and to take care of water losses through evaporation. 10

The liquid condensate from tubes 53 will drain into header 28 (Fig. 6) and will be returned to the boiler in a manner now to be described. As previously described, trap 31 is connected to line 30 between condenser 27 and boiler 10. An 20 equalizing passage 38 between trap 31 and condenser 27 is controlled by valve 67 in the trap; a passage 35 between the trap and boiler is controlled by valve 68 in the trap. If it is assumed that trap 31 is empty, then float 62 will be in 25 its lowest position. The valve 68 will be in closed position against the steam pressure in pipe 35 and valve 67 will be retained in open position so that the pressure in trap 31 will be substantially the same as the pressure in condenser 27. 30 Check valve 34 will be closed by the pressure from boiler 10. Check valve 41 is also closed due to the greater pressure in the trap (which is substantially the same as condenser pressure) than exists in the evaporator. Since trap 31 35 and condenser 27 are substantially at the same pressure, check valve 33 will be open due to the head of liquid in pipe 30; and inasmuch as trap 31 is lower than the condenser, condensate will flow by gravity from header 28 of the condenser, 40 through pipe 30, check valve 33 and pipe 32 into the trap. As the level of liquid rises in 31, the float will rise until, as hereinbefore explained, the weight 64 trips, thereby closing valve 67 and opening valve 68. Thereupon, steam 45 pressure from pipe 35 will enter the trap through valve 68 and exert a pressure on the liquid therein. Check valve 33 will immediately close and valve 41 remain closed since the boiler pressure is much higher than either condenser or evaporator pressure. The trap and boiler will then be under the same pressure and since the trap is higher than the top of the boiler, the head of liquid will cause check valve 34 to open and the liquid will flow through pipes 32 and 30 into 50 the boiler by gravity, thereby providing for boiler feed. As the trap empties the float will drop, thus causing weight 64 to fall to the other side, whereupon valve 68 will close and valve 67 open 55 so that the cycle may be repeated. While this gravity arrangement is illustrated in connection with the system herein disclosed, it is apparent that a pump or other analogous means may be substituted. 60

As the refrigeration process is carried on, the 65 water which is evaporated from tubes 29 of the heat exchanger, must be replaced. For this purpose, applicant provides a novel method and apparatus automatically for replenishing the liquid in the heat exchanger. The operation is carried on by a device operating in accordance with hydrostatic and thermal principles and eliminates a mechanical expansion valve with its attendant troubles. The operation will now 70 be described. A well 43 is provided for accumu- 75

lating condensate fed by pipe 30. Pipe 70 rises vertically a predetermined distance from well 43 to separator 44. From the separator, pipe 72, as illustrated, extends down and upward, in the form of a U and thence, horizontally to a point at which it drops vertically to the top of header 23 just above the uppermost trough 60. From separator 44 another pipe 71 rises vertically to a predetermined height, then, as illustrated, drops to a point well below the level of the evaporator, proceeds horizontally and then rises to connect with the bottom of header 23. At the lowest point in the last piping series, and adjacent the vertical section of pipe 71 leading to the bottom of header 23, is connected a pipe 73 which, in practice, may parallel pipe 71 from the point of connection to and into header 23. As illustrated in Fig. 5, pipes 71 and 73 terminate within header 23 at a height above the bottom thereof, at which it is desired to maintain the level of liquid in the header. The pipe 71 is exposed to the heating effect of the surrounding air to assure boiling of liquid in the vertical section of the pipe leading into header 23, while pipe 73 is suitably insulated to prevent such boiling action.

The action of returning liquid from the condenser to the evaporator is as follows: Hot condensate collecting in well 43 rises in tube 70, which may be insulated to prevent its cooling. As the condensate rises in pipe 70, it approaches the evaporator pressure and will proceed to a point at which it begins to boil due to the lowered pressure. The vapor is separated from the liquid in the separator 44. The separated liquid drops into the trap formed by the U bend in pipe 72 and then proceeds to build up a supply of fluid in piping 72 leading to the point of entrance at the top of the evaporator. The piping is so arranged that, in practice, the height of the column of liquid in pipe 70, plus the vertical height of the column of liquid in the trap portion of piping 72, is sufficient to balance the difference between the pressures in the condenser and evaporator. Thus, as more water from well 43 boils and supplies liquid to pipe 72, the balance will be disturbed and cause a corresponding amount to enter the evaporator. This will be carried on until the boiling action in the pipe 70 ceases, whereupon, the balance will be restored and no further liquid enter the evaporator.

The vapor from separator 44 passes into pipe 71. If there is sufficient water in the evaporator, the level in the bottom of the header will be above the point at which pipes 71 and 73 terminate. Pipes 71 and 73 will be filled with liquid and trap the vapor from separator 44 in the pipe 71. This will build up a pressure at the separator 44 so that the boiling action there will stop. As a result, no more water will flow from the separator into pipe 72, since the pressure is sufficient to retain the liquid within pipe 70. The vertical portions of pipes 71 and 73 which rise into the evaporator should be kept sufficiently hot so that the liquid therein will always tend to boil. As a result, when the water in the evaporator boils and the level in the bottom of header 23 decreases, the liquid in pipes 71 and 73 will also tend to boil away, thereby relieving the pressure in the line 71 and separator 44. As this pressure is released, boiling will again take place in pipe 70 and liquid allowed to flow into line 72 and into the evaporator until the level is again restored to the point where liquid once again flows into pipes 71 and 73 to build up a pressure

in line 71 sufficient to stop further boiling in pipe 70.

This system normally operates under a relatively high vacuum, to wit, about 5" of mercury, absolute pressure, in the evaporator and 2" of mercury, absolute, in the condenser. In practice, some leakage of air will normally occur. As a result, if air and other gases, which make their way into the system, are not removed, a pressure will be built up to the point where further operation becomes practically impossible. To remove or purge these gases, applicant provides aspirator 50 in water line 49. A pipe 56 leads to the aspirator 50 from the upper part of discharge header 28 of the condenser, the place at which gases tend to collect (see Fig. 6). The water flowing through the aspirator entrains and collects these gases and discharges them to the atmosphere with the spray water discharged from header 48.

To keep the system purged of gases during the season when refrigeration is being used intermittently, a thermostatic switch 74 (Fig. 2) and a small heater 75 are placed in a container 76 (Figs. 1 and 6), connected to the bottom of header 28 by tube 77. A small amount of water drains from the condenser into container 76. The heat from heater 75 keeps this water constantly boiling. The thermostatic switch 74 is set so that it remains open as long as the temperature of the boiling liquid is below a predetermined point, for example, 110° F. If air collects in condenser 27, the pressure on the liquid in container 76 is increased so that the boiling point of the liquid is thereupon increased. When it increases beyond the predetermined point, say 110° F., the switch 35 will close an electrical circuit, which will later be described in detail, and cause water valve 51 to open, whereupon the aspirator 50 will function to purge the condenser. When a sufficient vacuum is again established, the switch will open and water valve 51 close. If desired, a pressure operated switch may be used instead of one operative responsive to temperature changes. As will be hereinafter pointed out, this circuit provides an auxiliary operating feature, designed primarily to keep the system purged during those periods when refrigeration is required at infrequent intervals.

In that it is desired to operate the purge intermittently and to maintain the system constantly under a vacuum, as previously explained, it is self-evident that some means must be provided to close the passage 56, whenever the aspirator is not functioning, to prevent air flowing back through spray header 48, aspirator 50, and pipe 56 into the condenser 27. For this purpose, a valve 169, similar in construction to valve 51 is provided. As contemplated by applicant, valve 169 and 51 will open simultaneously in a manner which will be explained hereinafter. While this means of positively opening and closing the passage 56 is preferred, applicant realizes that it would be possible to accomplish the same result by placing a check valve in pipe 56 and locating the valve 51 between the aspirator 50 and the spray header 48. However, with such an arrangement, it is apparent that if the check valve should for any reason become inoperative, the system would be flooded with water, whereas with applicant's preferred arrangement, the only damage which would result from non-operation of valve 169 would be the filling of the condenser with air. Although this would cause excessive use of water for purging, no serious damage could be done to 75

the system, nor would the system necessarily become inoperative.

- It will be apparent from the foregoing, therefore, that the only boiler water lost to the system 5 will be that expelled with the gases during the purging operation. Such loss may be made up by a suitable feed arrangement to the boiler, for example, feed line 158 leading from a desired outside source under control of valve 159.
10. Under winter operating conditions, when heating is desired instead of cooling, and with no reference to controls which will be hereinafter described, valve 19 will be retained closed and valve 39 open. Steam from boiler 10 will flow through pipe 16, pipes 35 and 38, valve 39 and header 69 (Fig. 5) into pipes 31. The steam will be discharged from pipes 31 through the holes therein, as hereinbefore described. These holes are arranged to direct the steam toward one end of each 20 U tube 29. As may be noted by reference to Fig. 5, the holes in tubes 31 are so positioned that the steam will enter tubes 29 over the upper edges of the troughs. The tubes will thereupon be heated and condensate will drain through the opposite ends, fill the troughs and collect in the bottom of header 23. Pipe 40 leading from the bottom of header 23 will fill and open check valve 41, close valve 33, and open valve 34, whereupon the water will drain by gravity back to the boiler. This is 25 due to the fact that the pressures in the boiler and heat exchanger are substantially the same and the head of liquid will be sufficient to cause the flow back to the boiler at the lower level.

An extension of pipe 35 is shown which may 30 lead to radiators of conventional design located in a garage, servants' quarters or other places which cannot be heated practically from a central heat exchanger.

Although it is desired, under winter operating 35 conditions, to "air bind" the condenser, diffusers and the head casing 20 to prevent the heating of these elements, it is also desired to keep the heat exchanger free from air so that it may function properly. For this purpose, a thermostatic air 40 vent 170, generally well known in the heating art, is connected through pipe 171 with condensate drain 40, and subjected to the hot steam vapors in 42. As long as the hot steam can affect the thermostatic element of the vent 170, the vent 45 will remain closed to the atmosphere. However, as air collects in the pipe 171 and vent 170 the thermostatic element cools off, opens a valve and allows the steam to force the air out of the heat exchanger. It is apparent, from a foregoing section 50 of this specification, that under summer conditions, the vent 170 would be open to the atmosphere at all times. To prevent air working its way into the system through the vent 170 under summer operating conditions), a check valve 172 is placed in the line 171. When the vent 170 is 55 open and the heat exchanger 42 is under vacuum, atmospheric pressure will keep the check valve tightly closed. If any radiators are connected on the extension of line 35, the possibility 60 of which was previously pointed out, it is necessary to insert a two-way thermostatic air vent 173 in pipe 17. This valve is similar to 170 but is arranged to break any vacuum existing in the system under winter operating conditions as well 65 as vent air as desired. Its operation is similar to vent 169, hence, no further description is thought necessary.

For the purpose of controlling the relative humidity of the air during the heating season, a 70 pan 160 (Figs. 1 and 5), containing a variable

amount of water, as will be hereinafter described, is placed in the duct 57, preferably above the heat exchanger device 42, and is supplied with heat from any desired source, as, for example, the steam pipes 165. A hygostatic switch 164, located in the space to be conditioned and responding to changes in relative humidity of the air therein, is adapted to close an electrical circuit which will open the water valve 162 and supply water to the pan 160 when the humidity becomes 10 too low. The heat from the steam in pipes 165 will, of course, evaporate this water, which water vapor will be absorbed by the air passing thereover, thereby increasing the relative humidity. As the humidity increases, hygostatic switch 164 15 will operate to break the circuit, thereby causing water valve 162 to close. It is obvious that an appreciable amount of time is required to heat up and vaporize the water, and similarly, there will be an appreciable interval before the hygostat 20 164 will respond to the increased humidity. A valve small enough to supply water at just the rate at which it could be evaporated by the heat and absorbed by the air would not be very practical. To prevent flooding, and more important, 25 to prevent over humidification, a float 163 responding to changes in the level of water in pan 160, and adapted to operate an electrical switch 166, is placed in the electrical circuit (to be described in detail later) in series with the hygostat 164. The float 163 will operate switch 166 to break the electrical circuit, hence, closing the valve 162 (as by a spring) as the level in pan 160 30 rises to a certain maximum. As the water evaporates, the level in 160 will decrease and the float 35 will fall. At a certain minimum, the float will close switch 166, and if hygostat 164 is still closed, the circuit will again be closed to open the water valve 162 to supply water to pan 160. Obviously, the float 163 in its preferred form, 40 will be set to operate between close limits, hence, supplying only a small quantity of water to the pan 160 before it operates to close valve 162. The float 163 in many cases will operate to open and close water valve 162 several times before the 45 hygostat 164 operates, indicating, of course, that further humidification is unnecessary. In this manner, a very fine and smooth control of humidity is assured.

The heat exchanger 42 is mounted within a 50 duct 57 (Figs. 1 and 3) so that air from fan 58 serving the system will be forced over the tubes 29 and be heated or cooled, depending upon whether the heating or refrigeration process is being carried on. After being heated or cooled 55 by contact with tubes 29, the air then proceeds through duct 57 to the space to be conditioned.

When air is being cooled by exchanger 42, as under summer requirements, moisture will be 60 condensed from the air. To prevent rusting and other deteriorative effects, eliminators 174 are provided in duct 57 below the heat exchanger. The eliminators 174 (Fig. 1) comprise a series of arcuate metal plates extending across the duct 57. The lower edge of each plate is turned 65 upwards, thereby forming a gutter. The plates are preferably mounted on an angle with the horizontal, so that moisture deposited on the tubes 29 may fall, collect in the gutters of the eliminator plates and drain to any desired common source.

Applicant's system has been designed to operate between certain pressure limits under winter operating conditions, as, for example, between 0 and 4 pounds per square inch, and to operate under 75

summer operating conditions, when steam is employed for refrigeration purposes, at pressures between different limits, as for example, between 10 and 14 pounds per square inch. This differential in pressure limits has been utilized by applicant in the design of a control arrangement adapted to complete the system and make it entirely safe in operation as well as automatic in its function.

10 Referring to Figs. 1 and 2, numeral 78 represents a duplex switch mounted on boiler 10 by pipes 80 and 81. The switch is of the type in which an electrical connection is made when the pressure in boiler 10 drops to a certain low pressure, for example, ten pounds per square inch gauge pressure, and is broken when the pressure rises to an upper limit, for example fourteen pounds per square inch. It is evident that the switch could be set to operate within any desired pressure range. The device, therefore, operates responsive to changing boiler pressures. It also operates responsive to changes in water level within the boiler, thus carrying out a second function. A float, not shown, in the body of device 15 78 is adapted to open the electrical connection shown in Fig. 2 when the level of water in boiler 10 drops below a predetermined point. This connection remains open until the boiler is again filled to a safe level, as through inlet 158 leading 20 from a desired source of supply. Sight glass 19 is mounted on the device to give a visual indication of the liquid level in boiler 10. Another pressure switch 82 is mounted on and connected to the boiler by a pipe 83. This switch 82 is 25 adapted to operate three electrical contacts 143, 119 and 120. Contacts 119 and 120 close and contacts 143 open when a pressure, for example, of 4 pounds per square inch is attained in the boiler. When the pressure drops to 0 pounds per square 30 inch, contacts 119 and 120 open and contacts 143 close. Contacts 143 control the supply of fuel to the burners during winter operation, contacts 120 the operation of the air circulation fan motor and contacts 119 the operation of the condenser fan 35 motor. A third pressure switch 84 is mounted on and connected to boiler 10 by pipe 85 and operates responsive to boiler pressure to control an electrical contact arm 126. When the boiler pressure rises, for example, to 13 pounds per square 40 inch, arm 126 will make a connection with contact 127 to open steam valve 19, admitting steam from boiler to nozzle 18. The arm will remain in contact until the pressure drops, for example, to 9 pounds per square inch when it will break contact 45 127 and make another connection at contact 132 to close valve 19.

Referring to Fig. 2, transformer 86 has its primary winding 87 across a source of 110 V. current. This line includes a two-pole hand switch 88 and 50 thermal switches 89 and 90. The closing of switch 88 energizes primary winding 87 making current available to the secondary circuit, whose operation will hereinafter be described.

A five-pole double throw switch, generally 55 designated 91, enables positive control of the system by an unskilled operative, under winter and summer conditions.

When the center and bottom row of contacts are connected, the system will function under 60 winter control, whereas if the center and top row of contacts are connected, the system will be under summer control.

By reference to Fig. 2, it will be noted that 65 secondary winding 100 of transformer 86 is arranged to give two low voltages, in practice, pref-

erably 20 and 25 volts, in respective circuit arrangements.

For purposes of illustration, pressure switch 82 is designated in two places, contacts 143 being shown located apart from contacts 119 and 120. In practice, the switches will be grouped in one container.

The control system will now be described, and operation under summer conditions first considered. Switch 88 is closed thereby energizing 10 transformer 86. The winter/summer switch 91 is closed on the summer side, with the center terminals connected to the upper terminals. The closing of switch 91 completes a circuit across the 110 V. line including leads 92, thermal switch 138, 15 leads 93, contacts 94 and 95 of switch 91, lead 96, heating element 75 and lead 97 back to switch 88. Element 75 thereupon heats up and starts the water boiling in its container 76, connected to discharge header 28 of the condenser as previously 20 described. If the system has been inoperative for some time, the condenser will be filled with extraneous gases and the boiling temperature of the water in container 76 will be high enough to 25 actuate contact arm 98 of thermostat 74 to make contact at 99, thereupon completing the following circuit: Secondary winding 100, lead 101, contact arm 98, contacts 99, lead 102, contact 103 and 104 of switch 91, condenser water valve 51 and valve 169 in parallel therewith, and lead 105 back 30 to secondary winding 100. The completion of this circuit will cause valve 51 and valve 169 to open simultaneously, whereupon, aspirator 50 will start purging the condenser. When the action of 35 the aspirator has produced a sufficient vacuum in the system so that the temperature of the boiling liquid in container 76 drops to a predetermined point, arm 98 will break its contact at 99, thereby shutting off water valve 51, and simultaneously closing valve 169. The arm 98 is so 40 arranged that it makes contact either at 99 or at 106, and it always is in one of these two positions. Assuming that thermostatic switch 107, located in the space to be conditioned, is closed, 45 thus indicating that the space requires refrigeration, and assuming that the burner pilot, not shown, is burning and pilot switch 108 is therefore closed, a circuit will then be completed as follows: Secondary 100, lead 101, thermostatic 50 arm 98, contact 106, fuel valve 14, pilot switch 108, room thermostat 107, lead 109, contacts 110 and 111 of switch 91, lead 112, switch 78 (closed below steam pressures of 10 pounds per square inch) and lead 113 back to the 20 V. contact of secondary winding 100. It is of note that leads 109, 112 and contacts 110, 111, under summer operations short circuit contacts 143 of switch 82 which is open above 4 pounds per square inch steam pressure. The completion of this circuit 55 opens valve 14 to admit fuel to burners 13 which will be ignited by the pilot, thereupon supplying heat to boiler 10. When valve 14 opens, to allow fuel to proceed to the burners, a mechanical connection closes limit switch 114, shown on Fig. 2 adjacent valve 14, whereupon the following 60 circuit is closed: Secondary winding 100, lead 101, switch 114, leads 115 and 102, contacts 103 and 104 of switch 91, condenser water valve 51, valve 169, and lead 105 back to secondary winding 100. This causes valves 51 and 169 to open, thereby 65 allowing water to flow through aspirator 50 and spray header 48 onto the condenser tubes. After the burners have been in operation awhile and the pressure in boiler 10 reaches 4 pounds per 70 75

square inch, pressure switch 82 operates to close connections 119 and 120, completing a circuit including the 110 volt line, lead 92, then in parallel through leads 93 and 116 and their respective contacts 94, 95 and 117, 118, respective switches 119 and 120, motor 121 of fan 52 and motor 122 of fan 58 respectively, leads 123 and 124 respectively and back to starting point through lead 125. This will cause air conditioning fan 58 and condenser fan 52 to operate.

When the pressure in the boiler reaches 13 pounds per square inch, contact arm 126 of pressure switch 84 moves to make contact at 121, closing the following circuit: 20 V. terminal of secondary winding 100, leads 113, 128 and 129, contact arm 126, contact 127, winding 130 of valve 19, and lead 131 back to secondary winding 100. The energization of winding 130 opens steam valve 19 and allows steam to enter nozzle 18, thereupon starting up the cooling or refrigeration action in the heat exchanger 42 which then functions as an evaporator, as previously described. If the pressure in boiler 10 rises to 14 pounds per square inch pressure switch 78 will open, thereupon breaking the circuit for operating fuel valve 14, which will then close, as by a spring. The closing of valve 14 causes switch 114 to open, as by a mechanical linkage arrangement, whereupon the circuit including water valve 51 and valve 169 will be broken and the valve caused to close. However, steam valve 19 will still remain open and continue to supply steam to nozzle 18. The consumption of steam, however, is normally relatively large with respect to the reserve capacity of the boiler. Hence, if room thermostat 107 is still demanding further cooling, boiler pressure will soon drop to 10 pounds per square inch, whereupon switch 78 will close, fuel valve 14 open, and water valve 51 and valve 169 open. Further, if the steam valve 19 is open and water valve 51 is closed, it is apparent the consequent sudden heating of condenser 27 would cause arm 98 to make contact at 99 almost instantaneously, hence, opening valves 51 and 169 as previously explained. If, however, the room thermostat opens, thus indicating that further cooling is not required, the fuel valve will remain closed and the pressure in boiler 10 continue to drop. When the pressure drops to 9 pounds per square inch, arm 126 of pressure switch 84 moves to make contact at 132 closing a circuit including 20 V. terminal of secondary winding 100, leads 113, 128, 129, arm 126, contact 132, winding 133 of valve 19 and lead 131 back to the transformer. The energization of winding 133 causes valve 19 to close, therefore cutting off the steam to nozzle 18. With steam valve 19 and fuel valve 14 closed, the pressure in boiler 10 will drop slowly until at 0 pounds per square inch, contacts 119 and 120 of pressure switch 82 will be broken thereby stopping motors 121 and 122 operating respectively condenser fan 52 and air conditioning fan 58. If it is desirable to keep the air conditioning fan 58 operating constantly, to insure circulation of air in the conditioned space, contacts 120 may be short circuited through leads 134 and 135 by closing hand switch 136.

Thermal switches 137 and 138 are provided in the leads 116 and 93 to protect the line and motor against overload.

To transform the system from summer to winter operation, it is only necessary to shift the arm of switch 91 from the upper to the lower set of contacts. If the system has been inoperative during the intermediate season when neither

heating nor cooling is required, air will have leaked into the system. This fact is taken advantage of, as previously pointed out, under winter conditions to "air bind" condenser 27 and diffusers 21 and 24 to prevent their heating. The shift of switch 91 to the lower contacts retains valves 51 and 169 closed so that the system cannot be purged by the aspirator, nor can the air escape from the condenser because of valve 169. The closing of switch 91 will cause a circuit to 10 be completed including secondary winding 100, lead 101, arm 98 of thermostat 74, contact 99, lead 102, contacts 103 and 139, lead 149, fuel valve 14, pilot switch 108, lead 141, contacts 142 and 110 of switch 91, lead 109, contact arm 143 of pressure switch 82, pressure switch 78 (closed below 10 pounds per square inch of steam-pressure) and lead 113 to the 20 V. contact of secondary winding 100. It is of note that under winter conditions, applicant desires to operate fuel valve 14 20 in response to boiler pressure only. For this reason, thermostat 107 is short circuited through leads 141, 109, and contacts 142, 110 of winter/summer switch 91. The completion of this circuit will open fuel valve 14 to cause the production of steam in boiler 10. When the boiler pressure rises to 4 pounds per square inch, switch 143 will open, thereby closing the fuel valve, and when the boiler pressure is reduced to zero, the fuel valve will again open, thus, steam for heating is constantly available.

A thermostat, generally designated 144, located in the space to be heated, controls the operation of motor 122 for air conditioning fan 58 and steam valve 39. Assuming the space requires heating, then movable arm 145 of thermostat 144 will make contact at 146, thereby completing a circuit including leads 101 and 147, contacts 148 and 149 of switch 91, lead 150, arm 145, contact 146, winding 152, and leads 128 and 113 to the 20 V. contact of secondary winding 100. Steam valve 39, operative responsive to the completion of this circuit, will thereupon open and admit steam to the exchange device 42, which now serves as a heat radiator. If the space becomes 45 too warm, the arm 145 will make contact at 153, thereby closing a circuit including leads 101 and 147, contacts 148 and 149, lead 150, arm 145, contact 153, winding 154, leads 128 and 113 to the 20 V. contact of secondary winding 100. Steam 50 valve 39 will thereupon close. While two circuits are provided for positively opening and closing valves such as 19 and 39, it is obvious that a spring type valve may be employed whereby a circuit will be completed for operating the valve 55 in one direction, the valve being operated in the other direction by spring action upon the breaking of the circuit.

When valve 39 is opened, as previously described, its operation by any suitable means 60 causes arm 155 to close a circuit, including the 110 V. line, leads 92 and 116, contacts 117 and 156, arm 155, lead 151, motor 122 of the air conditioning fan 58 and leads 124 and 125 back to the line. The closing of this circuit starts fan 58 in 65 operation to cause air to circulate throughout the interchanger and be discharged within the area to be conditioned. When valve 39 closes, as hereinbefore described, switch 155 will open and the fan 58 becomes inoperative.

The hygrostatic switch 164, as previously pointed out, operates to control the relative humidity of the air within the space to be conditioned. To carry out the humidification process, it is necessary that air be flowing over the 75

humidifier to absorb water vapor. As previously shown, the fan 58, under winter operating conditions, can only be running when the steam valve is open. Further, when the steam valve is open, 5 the contact 143 of pressure switch 82 will normally be closed, and the fuel valve open. The humidifier circuit is placed in series with the contact 143 of pressure switch 82, so that it will be inoperative unless this contact is closed. If 10 it is assumed that contact 143 is closed and that there is no water in tank 160, then contact 166 will be closed, and, assuming further that the hygostatic switch 164 is closed, indicating that 15 humidification is required, a circuit will be completed including the 20 V. terminal of secondary winding 100, lead 113, pressure switch 18 (closed below 10 pounds per square inch steam pressure), contact 143, lead 109, contacts 110 and 142 of 20 switch 91, lead 141, pilot switch 108, lead 167, hygostatic switch 164, contacts 166, operating 25 responsive to float 163, water valve 162, leads 168 and 101 back to the secondary winding 100. Energizing this circuit causes the water valve 162 to open and supply water to the humidifier pan 160. As was explained before, the float 163, 30 responding to the water level in humidifier pan 160, will open contacts 166, when the water level reaches a predetermined maximum, thereby breaking the circuit. Valve 162 will be arranged to close under the action of a spring or weight. As the level decreases, the float will close contacts 166 at a predetermined minimum, thereby again closing the circuit and opening valve 162. It will be understood that this cycle may be 35 repeated several times before the hygostatic switch 164 operates to break the circuit. It is apparent that if the pressure switch 82 operates to open contacts 143 to cut off the fuel supply, this will also operate to break the circuit including valve 162, whereupon the valve will close.

40 Applicant specifically reserves the right to file other applications covering the subject matter disclosed herein relating to the heat exchange device, the method of returning liquid from the condenser to the evaporator, and various other matter herein disclosed but not claimed.

50 Since certain changes in carrying out the above process and in the constructions set forth, which embody the invention may be made without departing from its scope, it is intended that all matter contained in the above description or shown in the accompanying drawings shall be interpreted as illustrative and not in a limiting sense.

55 Having described my invention, what I claim as new and desire to secure by Letters Patent of the United States, is:

60 1. An air conditioning apparatus of the character described, comprising a source of steam, a first path for steam from said source, and means including a steam ejector in communication with a heat exchange device whereby steam supplied through said path to said ejector will cause the evaporation of liquid within the device to produce refrigerating effect within the device, and another path for supplying steam from said source into said device thereby to produce heating effect within the device.

70 2. An air heating and cooling system, comprising means for producing steam, a heat transfer unit, means for circulating air in contact with said unit, means including a steam ejector for evaporating a liquid to decrease the temperature within said unit under summer operating conditions and means for supplying steam into appa-

ratus serving said unit for increasing the temperature thereof under winter operating conditions.

3. An air heating and cooling system, comprising means for supplying steam to an ejector, a heat transfer unit in communication with the ejector, the discharge of steam within the ejector being adapted to evaporate liquid within the unit to cause a reduction in temperature within the unit and means for supplying steam directly to the unit, to cause a heating thereof. 5

4. In a system for heating and cooling enclosures, a source of steam, steam ejector apparatus in communication with a heat transfer unit, means for discharging air over said unit, means operative responsive to steam pressure between certain predetermined limits for admitting steam to the ejector apparatus whereby the unit will be cooled by the evaporation of liquid therein, and means operative responsive to changes in temperature within the enclosure for admitting steam to the unit to cause a heating thereof. 15

5. In an air conditioning system, a heat transfer device, a fan for discharging air over said device, a steam ejector in communication with said device, means for supplying steam to said ejector whereby liquid within said device will be evaporated and said device will be cooled, and other means for admitting steam directly to said device whereby it will be heated. 25

6. In an air conditioning system, a heat transfer device, a steam ejector in open communication with said device, a source of steam, means for admitting steam from said source to said ejector whereby a liquid within said device will be evaporated to cool the device, means for admitting steam directly to said device whereby the device will be heated, and a fan for discharging air over said device. 35

7. In an air heating and cooling system, a heat transfer unit, a steam ejector in communication with said unit, a source of steam, a first circuit for supplying steam to said ejector to cause evaporation of liquid within said unit whereby said unit will be cooled, and a second circuit for supplying steam directly into said unit whereby it will be heated. 40

8. In an air heating and cooling system, a heat transfer unit, means for retaining a volume of liquid in said unit, a steam ejector in communication with said unit, means for supplying steam to said ejector whereby the liquid in the unit will be evaporated and the unit cooled, other means for supplying steam into the unit whereby the unit will be heated, and a fan for discharging air over said unit. 50

9. An air heating and cooling system comprising a source of steam, a heat transfer unit, a steam ejector in communication with the unit, means operative responsive to steam pressure within certain limits for admitting steam to said ejector whereby liquid in the unit in communication therewith will be evaporated and the unit cooled, and other means for admitting steam to said unit for causing a heating thereof. 60

10. In a system for heating and cooling an enclosure, a source of steam, a heat transfer unit, a steam ejector in communication with said unit, means for admitting steam at certain pressures to said ejector, means for admitting steam at other pressures directly to said unit, the admission of steam to said ejector being adapted to cause evaporation of liquid within said unit to cool said unit, the admission of steam directly to said unit being adapted to cause a heating of the 70 75

unit, and a fan for discharging air over the surfaces of said unit.

11. In a heating and cooling system, a heat transfer device, including a plurality of tubes, means for retaining a desired quantity of liquid in the bottom of said tubes, a pump in communication with said device, said pump being adapted to cause evaporation of said liquid within said tubes, thereby to cool said device, means for admitting vapor directly to said device to cause a heating thereof, and means for discharging air over the surfaces of said device.

12. In an air heating and cooling system, a heat transfer device, including a receptacle for fluid means for retaining a volume of liquid in said receptacle, a means in communication with said device for reducing the pressure therein under certain conditions, means for discharging a vapor within said device under other conditions, and means for passing air over the surfaces of said device.

13. In a heating and cooling system, a heat

transfer device, including a plurality of tubes, means for retaining a desired quantity of water in the bottom of the tubes of said device, a steam ejector in communication with said device, a source of steam, means for admitting steam from said source to said ejector whereby a portion of the water in said device will be evaporated and the device cooled, other means for admitting steam from said source directly to said device, whereby the device will be heated, and means for discharging air over the surfaces of said device.

14. An air conditioning apparatus of the character described, comprising a source of steam, a first path for steam from said source, and means including a steam ejector in communication with a heat exchange device whereby steam supplied through said path to said ejector will cause evaporation of liquid to produce refrigerating effect within the device, and another path for supplying steam from said source, thereby to produce heating effect within the device.

CARLYLE M. ASHLEY.

CERTIFICATE OF CORRECTION.

Patent No. 2,010,001

August 6, 1935.

CARLYLE M. ASHLEY.

It is hereby certified that error appears in the printed specification of the above numbered patent requiring correction as follows: Page 3, first column, line 7, for "diffuse" read diffuser; page 5, first column, line 58, after "170" insert the parenthesis mark (; page 9, first column, line 15, claim 12, for "fluid" read liquid; and line 16, strike out the article "a"; and that the said Letters Patent should be read with these corrections therein that the same may conform to the record of the case in the Patent Office.

Signed and sealed this 12th day of November, A. D. 1935.

Leslie Frazer

Acting Commissioner of Patents.
